CLAIM

The ornamental design for a cracker, as shown and described.

DESCRIPTION

FIG. 1 is a perspective view of a cracker;

FIG. 2 is a top plan view of the cracker of FIG. 1;

FIG. 3 is a bottom plan view of the cracker of FIG. 1;

FIG. 4 is a left side elevation view of the cracker of FIG. 1;

FIG. 5 is a right side elevation view of the cracker of FIG. 1; and,

FIG. 6 is a front elevation view of the cracker of FIG. 1.
